UNITED STATES PATENT OFFICE.

EDWARD L. BOWERS, OF ORANGE, MASSACHUSETTS, ASSIGNOR TO THE NEW HOME SEWING MACHINE COMPANY, OF ORANGE, MASSACHUSETTS, A CORPORATION OF MASSACHUSETTS.

BOBBIN-CASE LATCH FOR SEWING-MACHINES.

SPECIFICATION forming part of Letters Patent No. 783,097, dated February 21, 1905.

Application filed October 17, 1903. Serial No. 177,412.

To all whom it may concern:

Be it known that I, EDWARD L. BOWERS, a citizen of the United States, and a resident of Orange, in the county of Franklin and State 5 of Massachusetts, have invented certain new and useful Improvements in Bobbin - Case Latches for Sewing-Machines, of which the following is a specification.

In that class of sewing-machines employing 10 a rotary or oscillating shuttle the bobbin and bobbin-case are located in operative position within a seat or opening in the face side of the shuttle and are removably retained therein, so as to be capable of being readily removed for 15 the purpose of resupplying the bobbin with thread or otherwise by means of a latch.

My present invention has for its object to provide an improved latch of the character referred to which will be simple in construction 20 and effective in operation; and to this end the invention consists in the novel features of construction and combinations of parts, as herein-after set forth in detail and pointed out in the claims.

25 Referring to the accompanying drawings, forming part of this specification, Figure 1 is a face view of a shuttle-raceway frame with a supported shuttle and bobbin-case and shows my improved bobbin-case latch in closed or 30 operative position for retaining the bobbin-case within the shuttle. Fig. 2 is a similar view showing the bobbin-case latch in an open or inoperative position and the bobbin-case removed from the shuttle. Fig. 3 is an edge 35 view of the parts, as shown in Fig. 1.

In the drawings the shuttle-raceway frame 1, detached from its normal operative position beneath the bed-plate of a sewing-machine, the rotary shuttle 2, supported to operate 40 within said raceway-frame, and the bobbin-case 3, supported within said shuttle, are all of usual construction and arrangement.

The bobbin-case 3 is adapted to be removably retained in a non - rotatable position 45 within the shuttle 2 by means of my improved latch, designated at 4. This latch is pivotally mounted upon the raceway-frame by a pivot-screw 5, so as to be movable to and from an

operative position in front of the bobbin-case 50 for removably retaining the latter within the shuttle and is also provided with a bifurcated portion 6 at its free end for loosely embracing a forwardly-projecting lip or flange 7 on the face of the bobbin-case and holding the latter 55 against rotation, the space between the latch and the bobbin-case being sufficient to permit of the free passage of the needle-thread loop in being carried around the bobbin to interlock with the under thread.

As a simple and effective means for locking 60 the latch in its said operative position I have provided the same with a spring locking-arm 8, having a locking pin or projection 9 adjacent to its free end, which is adapted to effect locking engagement with a suitable stationary 65 part, such as the frame 1, by entering a seat or opening 10 therein. When the said pin 9 of the locking arm 8 is seated within the opening 10, the latch will be locked in its operative position relatively to the bobbin-case, as shown 70 in Fig. 1. When, however, it is desired to remove the bobbin-case from the shuttle, the operator will draw the free end of the locking-arm outwardly from the face of the frame 1 a sufficient distance to disengage the pin 9 75 from the opening 10, as shown in Fig. 3, and then swing the latch upon its pivot away from operative position in front of the bobbin-case, as shown in Fig. 2.

In order that the pin 9 of the locking-arm 80 may be readily entered into its seat 10 in the frame 1 upon the closing of the latch, I have formed a notch 12 in the outer edge of the frame 1 in a position in the path of movement of the pin 9, the lower wall of which 85 notch is inclined and presents a cam-surface for engaging with the said pin 9 upon the closing of the latch and forcing the same outwardly as it is moved thereover until it reaches a position opposite the seat 10, into 90 which latter it will then snap under the action of the spring-arm carrying the same.

The spring locking-arm 8, as herein shown, is made integral with the latch, although it will be obvious that it might be formed in a 95 separate piece and be suitably attached to the

latch. As a convenient means for operating the locking-arm, both in swinging the latch upon its pivot and in withdrawing the pin 9 from locking position within the seat 10, I 5 have provided the same with a small knob or handle 14 adjacent to its free end, which may be conveniently grasped by the operator.

What I claim is—

1. In a sewing-machine, the combination 10 with the shuttle and the bobbin-case, of a two-armed bobbin-case latch mounted and operative upon a single pivot, one of the arms of said latch constituting the latch proper and being movable to and from an operative position for retaining the bobbin-case within the 15 shuttle and the other arm being a spring locking-arm, and a stationary part having means for locking engagement with said locking-arm and with which locking engagement is 20 effected by a movement of the locking-arm substantially at right angles to the normal path of movement of the latch-arm.
2. In a sewing-machine, the combination

with the shuttle and with a bobbin-case having a projection on its face side, of a two- 25 armed bobbin-case latch mounted and operative upon a single pivot, one of the arms of said latch constituting the latch proper and being movable to and from an operative position for retaining the bobbin-case within the 30 shuttle and also having a bifurcated portion to receive the said projection on the bobbin-case, and the other arm of said latch being a spring locking-arm, and a stationary part having means for locking engagement with 35 said locking-arm and with which locking engagement is effected by a movement of the locking-arm substantially at right angles to the normal path of movement of the latch-arm.

Signed at New York, in the county of New 40 York and State of New York, this 30th day of September, A. D. 1903.

EDWARD L. BOWERS.
